(57) **CLAIM**

The ornamental design for a motor valve as shown and
described.

DESCRIPTION

FIG. 1 is a front view of a motor valve;

FIG. 2 is a top view thereof;

FIG. 3 is a top perspective view thereof;

FIG. 4 is a left view thereof;

FIG. 5 is a right view thereof;

FIG. 6 is a back view thereof;

FIG. 7 is a bottom view thereof; and,

FIG. 8 is a bottom perspective view thereof.

The broken lines in the drawings depict portions of the
motor valve that form no part of the claimed design. The
dot-dash broken lines depict portions of the motor valve that
form no part of the claimed design.

1 Claim, 8 Drawing Sheets
